(57) **CLAIM**

We claim, the ornamental design for a baffle for luminaire, as shown and described.

DESCRIPTION

FIG. 1 is a perspective view of a baffle for luminaire, showing our new design, as disposed on a luminaire;
FIG. 2 is a side elevation view thereof, the opposite side being a mirror image thereof;

FIG. 3 is a front elevation view thereof;

FIG. 4 is a rear elevation view thereof;

FIG. 5 is a top plan view thereof; and,

FIG. 6 is a bottom plan view thereof.

The broken line illustration of portions of the baffle and luminaire illustrate environmental structure and form no part of the claimed design.
